WILLIAM WISHART, OF CLINTON, IOWA, ASSIGNOR TO CLIMAX ENGINEERING COMPANY, A CORPORATION OF DELAWARE

COMBINED STRAINER AND CHECK VALVE

Application filed December 21, 1925. Serial No. 76,678.

This invention relates primarily to an improved combination suction strainer and check valve construction adapted to be used in one housing connected in a pipe leading from the expansion coil of a refrigerating unit to the compressor.

It is an object of this invention to provide a combined suction strainer and check valve mounted within the same housing to eliminate the leakage ordinarily encountered in pipe joints.

It is also an object of this invention to provide a strainer and check valve unit adapted for use in the pipe connecting the expansion coil and compressor of a refrigerating unit.

It is a further object of this invention to provide a housing adapted to be connected in the pipe line between the expansion coil and the compressor of a refrigerating unit, said housing having mounted therein an improved suction strainer or oil separator device through which the expanded refrigerant must pass before being permitted to pass through a check valve also mounted in said housing between the strainer and the outlet pipe leading to a compressor.

It is an important object of this invention to provide a simplified strainer and check valve construction adapted to be enclosed by a single housing which is connected in the pipe line leading between the exhaust end of an expansion coil and the intake end of a compressor forming part of a refrigerating unit.

Other and further important objects of this invention will be apparent from the disclosures in the specification and accompanying drawings.

The invention (in the preferred form) is illustrated in the drawings and hereinafter more fully described.

On the drawings:

Figure 1 is a fragmentary top plan view of an improved suction strainer and check valve unit embodying the principles of this invention.

Figure 2 is a vertical detail section taken on line II-II of Figure 1 showing parts in elevation.

Figure 3 is an enlarged vertical detail section of a modified form of suction strainer.

As shown on the drawings:

The reference numeral 1 indicates a supporting framework or base forming a part 55 of a refrigerating unit. Secured to the framework 1 by means of bolts 2 or other suitable means is the apertured base plate 3 which is integrally formed on the lower end of a housing or casing 4. The housing 4 is hollow and is provided with an inner flange or partition ring 5 which divides the interior of the housing into a lower intake chamber 6 and an upper outlet chamber 7. The upper portion of the housing 7 is provided with an outlet passage or opening 8 above the partition 5 and leading outwardly from the upper discharge chamber 7. Connected to one side of the lower portion of the housing 4 is an inlet pipe 9, the other 60 end of which is connected with the exhaust end of an expansion coil of a refrigerating unit to permit the expanded refrigerant from the expansion coil to flow through the pipe 9 into the lower intake chamber 6 of 65 the housing 4.

As clearly shown in Figure 2, one wall of the housing 4 is provided with a circular groove 10 around the outlet opening 8 to receive the circular flange 11 which is integrally formed on one side of a mouthpiece or hood 12. Secured against the grooved face of the housing 4 to cover the outlet opening 8 is a flap valve 13, one portion of which is held in position by means of a retaining screw 14 or other suitable means. The valve 13 is adapted to act as a check valve and is positioned within the recess 15 formed by the flanges 11 of the mouthpiece 12. The mouthpiece 12 is integrally formed 80 on one end of an elbow or pipe 16 the other end of said pipe 16 being connected to communicate with the intake chamber of a compressor 17 forming a part of the refrigerating unit. The pipe 16 is secured to the compressor 17 by means of bolts 18 or other suitable means.

The upper end of the housing 4 is open and is adapted to be closed by means of a top plate or cover 19 which is rigidly se- 100

cured to the top of the housing by means of bolts 20 or other suitable means. The top plate or cover 19 is provided with a central opening 21 which is normally closed by means of a threaded plug 22. Integrally formed 5 on the inner face of the cover 19 is a hollow sleeve 23 which projects through the housing outlet chamber 7 and into the upper end of the housing intake chamber 6. Integrally formed 10 on the lower portion of the sleeve 23 is a flange 24 which fits tightly into the housing flange 5 and thus separates the two chambers 6 and 7. The sleeve 23 is provided with an outlet opening 25 which communicates 15 with the upper chamber 7 of the housing 4. The lower end of the sleeve 23 is open and communicates with the lower housing chamber 6 through a strainer.

The strainer comprises a cylindrical steel shell 26 the upper end of which is secured 20 to and fits tightly around the lower end of the sleeve 23. Mounted within the strainer shell 26 at spaced intervals are a plurality of screens 27 dividing the shell into a plurality of chambers or compartments, each of which 25 is filled with a packing 28.

By referring to Figure 2 it will be noted 30 that the housing 4 which is connected between the exhaust end of a refrigerating unit expansion coil and the intake end of a compressor is constructed to contain both a suction strainer and a check valve mechanism, thus affording a construction adapted to 35 eliminate leakage, which is usually encountered when a plurality of pipe joints are provided in the refrigerant circulating system of a refrigerating unit.

Figure 3 covers a modified form of a strainer unit adapted for use in the refrigerant 40 circulating system of a refrigerating unit. The modified form of the device comprises a cylindrical casing or housing 29, the upper and lower ends of which are closed by means of grooved closure plates or heads 30. The 45 heads 30 are apertured and connected by means of connecting bolts 31. The bolts 31 act to securely hold the heads 30 engaged against the ends of the housing 29. Projected into an opening in the lower portion 50 of the housing 29 is one end of a refrigerant intake pipe 32, the other end of which projects into a manifold 33. The manifold 33 is connected by means of a pipe to the 55 exhaust end of an expansion coil of a refrigerating unit. Projecting into an aperture in the upper portion of the housing 29 is one end of a pipe 34, the other end of which is connected with the intake end of a compressor forming a part of a refrigerating unit.

60 The central portion of the inner face of the upper head 30 is provided with a recess 35 in which the upper end of a compound or multiple cylindrical screen 36 is seated. The screen 36 comprises a plurality of concentric cylindrical screens secured together

to provide a sleeve which projects downwardly into the upper portion of the housing 29 to a point below the opening in which the pipe 34 is engaged. Projecting into the lower end of the multiple screen sleeve 36 70 is the upper end of a steel cylindrical shell 37. Securely mounted within the shell 37 at spaced intervals are a plurality of sets of screen plates 38, said groups of screen plates separating the interior of the shell 37 into a plurality of compartments each of which is filled with a packing 39. Rigidly secured around the upper portion of the shell 37 below the lower end of the screen sleeve 36 75 are a pair of felt retaining rings 40 separated by a felt packing 41. The felt retaining rings 40 and the packing 41 separate the interior of the housing 29 into a lower intake chamber 42 and an upper outlet chamber 43.

80 The operation is as follows:

In a refrigerating unit the refrigerant, after entering the expansion coil, is adapted to be discharged through the exhaust end of the expansion coil and is permitted to flow 85 back to the compressor through the pipe 9. Connected between the pipe 9 and the elbow pipe 16 is the improved combination strainer and check valve mechanism. The expanded refrigerant from the expansion coil flowing 90 through the pipe 9 enters the lower portion of the housing 4 and flows into the lower chamber 6 around the strainer mechanism within said chamber. The refrigerant is adapted to be drawn by means of suction upwardly 95 through the screens 27 and through the packing 28 separating said screens to be purified before entering the chamber within the sleeve 23. The impurities in the refrigerant having been removed by the 100 improved strainer, said refrigerant, is permitted to flow from the interior of the chamber outwardly through the discharge port or opening 25 into the upper chamber 7 of the housing 4 which upper chamber 7. 105 provides for the accumulation of purified refrigerant to insure uniform outflow past the valve 13 during suction of the compressor. By thus permitting of the accumulation of a supply or head of refrigerant between the 110 strainer and the outlet valve, heavy suction upon the strainer itself is avoided and greater uniformity in the supply of refrigerant to the compressor is insured. From the chamber 7 the purified refrigerant is adapted to 115 escape through the discharge port 8 past the flap valve 13 which is opened by the flow of the refrigerant and by the suction action produced in the elbow pipe 16. After passing the open valve 13 the purified refrigerant enters 120 the mouthpiece 12 and flows through the elbow pipe 16 into the receiving chamber of the compressor 17. It will thus be seen that the improved invention provides but a single 125 housing for both the suction strainer and the 130

check valve mechanism thereby eliminating leaks which often occur when pipe joints are extensively used.

In the modified form of the device illustrated in Figure 3 the expanded refrigerant from the exhaust end of the expansion coil of a refrigerating unit is adapted to flow through the manifold 33 and the pipe 32 into the lower chamber 42 of the housing 29. The refrigerant is then permitted to be drawn upwardly through the sets of screens 38 and through the packing 39 separating said screens so that the impurities in the expanded refrigerant are removed, permitting the refined or screened refrigerant to enter the chamber provided by the cylindrical sleeve screen 36. From the screen 36 the refrigerant is permitted to be drawn through the walls of the sleeve to enter the upper housing chamber 43 from which chamber the purified refrigerant is permitted to flow through the pipe 34 back into the compressor of a refrigerating unit.

I am aware that many changes may be made and numerous details of construction may be varied through a wide range without departing from the principles of this invention, and I therefore do not purpose limiting the patent granted hereon, otherwise than necessitated by the prior art.

I claim as my invention:

1. The combination with a housing adapted to be connected between the expansion coil and compressor of a refrigerating unit, a sleeve in said housing dividing the housing into upper and lower chambers, a shell in said housing connected to said sleeve and extending downwardly therefrom into said lower chamber, a plurality of screens in said shell, and packing in said shell between said screens, said upper chamber provided for carrying a head of purified refrigerant.

2. A strainer and check valve mechanism comprising a housing having a discharge port therein an apertured sleeve projecting into said housing to divide the interior thereof into lower and upper chambers, a shell secured to said sleeve and projecting into the lower chamber, said upper chamber serving to permit a head of purified refrigerant to be carried in the upper end of said housing, a plurality of spaced screens in said shell, packing in said shell between said screens, and a valve on said housing for controlling the flow of the refrigerant through said discharge port.

3. A strainer and check valve mechanism comprising a chambered housing, a refrigerant inlet pipe connected to said housing to communicate with one of the chambers thereof, a refrigerant head in another chamber of said housing, a discharge port in said housing communicating with said refrigerant head carrying chamber of said housing, an apertured sleeve projecting into the housing

and communicating with said port, a shell within said housing connected with said sleeve, a plurality of spaced screens in said shell, packing separating said screens, an elbow pipe connected to said housing, and a control valve in said elbow pipe and mounted on said housing for governing the flow of a refrigerant through said exhaust port.

In testimony whereof I have hereunto subscribed my name.

WILLIAM WISHART.
